UNITED STATES PATENT OFFICE

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SHUTTLE CHANGER LOOM

Application filed April 6, 1931. Serial No. 528,198.

This invention relates to improvements in shuttle changing looms and it is the general object of the invention to provide means whereby a shuttle may enter a box with greater accuracy at the time of shuttle exchange.

In a form of shuttle changing loom which has gone into general use there is provided a magazine located above the lay which is arranged to release a full shuttle when the weft of the running shuttle is exhausted. The lay is provided with two shifting shuttle boxes which are normally at rest but which at the time of change are raised, the upper box to receive the fresh shuttle and the lower box to receive the incoming exhausted shuttle. At a subsequent point in the cycle of the operation these boxes are lowered so that the fresh shuttle is brought opposite the lay while the exhausted shuttle is discharged into an appropriate receiver. In connection with this form of changing mechanism there is used a binder which is stationary with respect to the lay and this binder is so proportioned and positioned as to hold the shuttles in proper position during shifting movements of the boxes.

Where high speed looms are used it is desirable to set the binder sufficiently close to the rear wall of the box so as to effect proper checking of the shuttle. When so set there is likelihood that the binder will interfere somewhat with the free gravitational downward movement of the fresh shuttle into the top box. It is an important object of my present invention to provide means which shall be brought into action by the movement of the boxes to act on the stationary binder and move the same away from the opposite part of the shuttle box, thereby providing sufficient clearance to permit the fresh shuttle to drop properly onto the box floor.

A more specific object of my invention is to provide a cam or other device having an inclined face to engage the binder as the boxes rise for the purpose of moving the binder forwardly, this cam passing out of controlling position relatively to the binder during the return of the boxes to normal position and prior to picking.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a top plan view of a lay having my invention applied thereto,

Fig. 2 is a front elevation taken in the direction of arrow 2,

Fig. 3 is a transverse vertical section on line 3-3 of Fig. 1 showing the boxes in normal down position,

Fig. 4 is a view similar to Fig. 3 but taken along line 4-4 of Fig. 1, and

Fig. 5 is a perspective view of a portion of the box structure.

The invention set forth herein relates more particularly to the type of loom shown in prior patent to Chevrette No. 1,753,233. The loom may include in this construction a lay 10 on which is guided for vertical movement a box structure designated generally at 11. 75 This structure has guide tongues 12 to enter guide plates 13 carried by the lay. By mechanism not shown herein but set forth in aforesaid patent the boxes may be moved vertically in order to effect a change of shuttles. 80 Under normal conditions when a sufficient supply of weft is present the box structure will be in the position shown in Fig. 3 with the upper box 14 in picking position and the lower box 15 below picking position.

A binder 16 is pivoted to the lay as at 17 and is held normally in rear position by a binder spring 18. The back of the shuttle box may be defined by a wall 19 against which the active shuttle 20 is pushed by the binder. 90 The binder has an upwardly extending outwardly curved set of fingers 21. A box cover 22 is pivoted as at 23 to the box structure and is acted upon by mechanism not shown to be raised to shuttle receiving position at the time 95 of replenishment.

The matter thus far described together with other structure shown in the drawings but not specifically described herein may be substantially the same in structure and op-

eration as set forth in the aforesaid patent. It is to be understood that the boxes will rise from the down position shown in full lines to the raised position shown in dotted lines in Fig. 3 when the shuttle change is to take place and that the upper box is defined in part by the binder 16 together with the extensions 21 and the wall 19 as shown in Fig. 4.

In carrying my invention into effect I provide the box with a cam 30 having an upwardly and rearwardly inclined surface 31 which normally lies below the binder as shown in Fig. 3. When in this position the active shuttle may be picked into and from the top box and the binder will act in the usual way. When a change of shuttle is called for, however, the box will rise as previously described and the cam will be moved from the full to the dotted line position shown in Fig. 3. The effect of this action is to move the binder away from the wall 19 so that it assumes the dotted line position shown in said figure. Under these conditions the top shuttle 'S' which is to be moved from a magazine not shown to the top box is free to move by gravity on to the floor 32 of the top box 14 and between the wall and the binder. During the subsequent downward movement of the boxes the cam moves out of controlling position with respect to the binder and the latter returns to its normal position where it can check the shuttles as they enter the top box. The protector finger P will be moved indirectly by the cam as the latter rises, but this will cause no inconvenience or substantial change in the operation of the loom. During the downward movement of the boxes the shuttle will be in correct relation with respect to the floor 32 so that the first pick of the fresh shuttle from the box will be correct.

From the foregoing it will be seen that I have provided a simple means to enlarge the top box at the time of replenishment whereby increased room is provided for the downcoming shuttle. It will also be seen that the cam which effects this result moves out of binder controlling position prior to picking.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a lay provided with a rising box to be lifted from normal down position to raised position to receive a new shuttle, a wall forming a part of the shuttle box, a binder stationary with respect to the lay and cooperating with the wall to define one dimension of the box, and means operative by upward movement of the box to move the binder away from the

wall to enlarge said dimension of the shuttle box, said means including an inclined face moving with the shuttle box and engaging the binder.

2. In a shuttle changing loom having a lay and a vertically shifting shuttle box movable from normal down position to raised shuttle receiving position, a binder stationary with respect to the lay defining a part of the shuttle box, and means operative by upward movement of the box to engage the binder and move the same in a direction to enlarge the box, said means comprising an inclined cam face fixed with respect to the rising box.

In testimony whereof I have hereunto affixed my signature.

AUGUSTIN J. CHEVRETTE.
